UNITED STATES PATENT OFFICE.

JULIUS KRAMER AND BERT D. WOLF, OF CHICAGO, ILLINOIS, ASSIGNEES TO PULLMAN COUCH COMPANY, OF CHICAGO, ILLINOIS, A CORPORATION OF ILLINOIS.

DRIER.

Application filed August 6, 1919. Serial No. 315,685.

To all whom it may concern:

Be it known that we, JULIUS KRAMER and BERT D. WOLF, citizens of the United States, residing at Chicago, in the county of Cook 5 and State of Illinois, have invented certain new and useful Improvements in a Drier, of which the following is a specification.

This invention relates more particularly to a drier for varnished woodwork such as 10 furniture or the like, but of course may have a more general use wherever applicable. The principal object of the invention is to provide a new and improved device of this kind by means of which articles can be 15 dried more quickly than if subjected only to the atmosphere.

Further objects of the invention are to provide a drier of this kind in which a circulation of air is produced within the drier 20 without subjecting the contents thereof to a direct draft; to provide adjacent upright passages in which a natural draft is produced by heating elements in at least one of them; to receive the incoming air directly from the 25 atmosphere so that no artificial moistening therefor is necessary; to eliminate fans, blowers and suction connections; to provide means for directing the air currents downwardly from the top and to thus evenly distribute them throughout the drier; and in 30 short to provide a drier of the construction described and claimed.

Referring now more particular to the drawings, Fig. 1 is a cross section of a drier 35 constructed in accordance with the principles of this invention; Fig. 2 is a view of one of the side walls, partly in section and partly in elevation; and Fig. 3 is a section through one of the flues in Fig. 2.

40 In the ordinary drying of varnished furniture or the like it takes from three or four days to a week or more, depending upon the paint or varnish used, in order that the coating may be dried or hardened sufficiently to 45 handle the articles successfully. If such articles are placed in a drier which receives heated air from a fan or blower the articles are dried unevenly, that is, more on one side than on the other, or more in one part of the 50 drier than in another and in either case the result is unsatisfactory. If the articles are placed in a substantially sealed enclosure which is artificially heated, the lack of circulation prevents the rapid drying. The 55 present invention is therefore designed and

intended to overcome all of these projections by providing a drier in which there is a natural or a definite air circulation from the top of the drier downwardly so that none of the articles will receive the direct impact of 60 fans or blowers, and with a discharge connection which receives the relatively cooler air from the bottom of the drier and directs it upwardly and outwardly therefrom producing a gentle, but still a positive and well 65 distributed circulation throughout the entire drier.

This drier comprises an enclosed chamber preferably in the form of a room with a floor 1, side and end walls 2 and 3, and a ceiling 70 4 having rounded corners 5 where the ceiling joins the side walls and having depending angularly disposed deflectors 6 parallel with the side walls and spaced some distance therefrom. In the case of a narrow room or a small drier these deflectors 6 may be joined at the center as shown in Fig. 1, which is the preferred construction. This room or drier may be made of any desired or suitable material and for a furniture drier only a wall 80 board or plaster covering is required.

Within the drier and spaced slightly from each of the side walls thereof is a partition 7, behind which is a heating coil 8, connected by means of pipes 9 with an outside 85 source of supply. At the bottom of the chamber or passage formed by each partition 7 is an inlet pipe 10 which extends from the exterior of the drier and has a 90 T-head with branches extending laterally in both directions below the heating coil 8. These branches 11 of the head are prefably graduated in size, as shown in Fig. 2, and at the upper edge are spaced inlets 12 through which air from the outside of the 95 drier may be admitted all along the full length of the drier below the heating coil. Of course this same result can be obtained in different ways, but the object of the construction is to insure a uniform distribution 100 of the air along the entire side of the drier.

Outside of each drier wall 2 is a wall 13 forming a vertical passage or passages 14 closely adjacent the wall 2 so that the heating coil 8 will usually cause an increase 105 of temperature in the passages 14.

At the bottoms of the passages 14 they are connected with the interior of the drier and through the passage formed by the inside partition 7 by means of funnel-shaped in- 110

lets 15 disposed below extensions 11 of the inlet pipe 10 as shown more clearly in Figs. 2 and 3. These inlets 15 have no communication with the passage formed behind the partition so that air is drawn directly from the bottom of the drier into the upright passages 14. These passages 14 may be restricted in width if desired, as by means of vertical partitions 16. An outlet or suction pipe 17 may be provided for the upper ends of the chamber 14, and it is contemplated that both these pipes and the inlet pipes 10 may be connected to a suitable suction or blower system if desired, but ordinarily 15 such connections are not required as the draft produced by the heating coil is sufficient to induce the proper circulation of air in the drier.

In operation it is necessary only to fill the 20 drier with the articles to be dried through the end doors (not shown) and to turn the heat on in the heating coils 8. This will cause the air to rise behind the partition 7, to be deflected inwardly at the ceiling of 25 the drier by the curved portions 5, and to be directed downwardly by the deflectors 6. The partitions 7 therefore not only 30 protect the contents of the drier from the direct heating of the coils 8 but they also form the upwardly directing passage for the incoming air current. Of course the heating coils cause an inflow of air through the openings 12 of the inlet pipe 10, and as 35 the cooler air in the drier sinks to the bottom it is drawn out of the drier by the discharging passages 14 which communicate with the drier at the bottom, and which may be slightly heated to assist in inducing an upward air current by means of the adjacent 40 heating coil 8, which however, is not necessary because even though the air at the bottom of the drier is cooler than that admitted in the top it is much warmer than the outside air so that a draft is produced 45 by the discharging passages 14 which communicate with the atmosphere at their tops.

By introducing the articles to be dried at one end of the drier and removing them at the other it can be kept continuously in 50 operation, and as there are no fans, blowers, or any parts to get out of working order, no manual attention is required. The pipe 10 preferably extends to the atmosphere outside of the factory or building in which 55 the drier is located, and this insures a constantly changing new air supply in the drier at all times.

We claim:

1. In a drier having opposite side walls, 60 a heating coil arranged the full length of each side wall, a partition adjacent the side wall enclosing the coil and extending adjacent the top of the chamber, means comprising a T-headed pipe with spaced openings 65 therein for admitting atmospheric air at

given distances along the side wall below the coil, and an outside partition having vertical passages which communicate at their lower ends with the interior of the chamber.

2. In a drier, a heating coil disposed along 70 the wall thereof, a partition spaced from the wall enclosing the coil, means for admitting air from the outside of the drier to the space behind the partition, said means including a central pipe with laterally diminishing extensions thereof below the coil having openings therein at spaced distances to insure the admittance of atmospheric air at all points along the said wall.

3. In a drier, a closed chamber, means including a heating coil and a pipe with inlet openings extending along the side of the chamber communicating with the atmosphere for causing an upward draft along the sides thereof, means extending from the 85 ceiling for deflecting the upward draft from each side downwardly within the drier, and passages parallel with the side walls and communicating with the bottom of the chamber to permit the escape of cooler air from 90 the bottom of the drier and to cause a circulation therein.

4. In a drier, the combination with a chamber formed at the top of opposite sides with a curved deflector and longitudinally 95 between the sides with a deflector extending downwardly from the ceiling, of draft inducing means at the sides of the chamber, a partition extending from the floor only part way to the ceiling and enclosing said means 100 for directing the draft upwardly at the sides, an inlet from the outside of the drier at the bottom of the partition, and an outlet at the bottom of the drier in which a draft is also induced by the said draft inducing 105 means.

5. A drier comprising an enclosure with opposite sides and a deflector extending from the ceiling parallel with the sides, including a partition extending from the bottom and terminating at a distance from the ceiling, means at the sides for causing an upward draft, and means at the upper edges along the sides for directing the draft toward the said deflector so that it is turned 115 downwardly in the drier thereby.

6. In a drier, a heating coil disposed adjacent the side wall thereof, a partition spaced from the side wall enclosing the coil to protect the contents of the drier directly 120 therefrom, and means including a pipe back of the partition with openings for admitting air from the outside of the drier at spaced distances apart below the coil.

7. In a drier, a closed chamber, a partition 125 adjacent the side wall thereof, means including a longitudinally extending pipe with openings forming communication between the space back of the partition at the bottom thereof and the outside of the drier, and 130

- means behind the partition for causing a draft from the outside of the drier through the pipe and to the bottom of the space behind the partition and upwardly toward the 5 top of the chamber.
8. In a drier, a wall having two air spaces, the outer air space communicating at the bottom with the inside of the drier, and the top of the inner air space communicating directly 10 and means including a perforated pipe forming communication for the inner air space at the bottom from the outside of the drier with the upper part of the drier chamber.
9. In a drier, a triple wall with air passages therebetween, the outer air passage communicating with the interior of the drier at the bottoms of the walls, the inner air passage communicating at its bottom with the atmosphere and at its top opening out into the upper part of the drier chamber, and heating means in one of the passages for causing an upward draft in them both. 15
10. In a drier, a triple wall forming parallel, vertical air passages, means forming an atmospheric inlet for the inside passages, a converging inlet for the outer air passages which extend between the inner and middle walls at the bottom of the drier, and means in one of the sets of air passages for producing an upward draft in them both. 20
11. In a drier, a triple wall forming parallel, vertical air passages, means forming an atmospheric inlet for the inside passages, a converging inlet for the outer air passages which extend between the inner and middle walls at the bottom of the drier, a heating coil in the inner air passages to cause a circulation of air in both passages, and means at the upper edges of the side walls and depending from the ceiling for directing the draft from the inner passages downwardly from the ceiling and toward the outlets at the bottom for the outer air passages. 25
